[57] CLAIM

The ornamental design for a bottle, as shown and described.

DESCRIPTION

FIG. 1 is a perspective view of the bottle of my design; FIG. 2 is a right side elevation view thereof, the left side elevation view being a mirror image thereof; FIG. 3 is a front elevation view thereof, the rear elevation view being a mirror image thereof; FIG. 4 is a top plan view thereof; and, FIG. 5 is a bottom plan view thereof.

The broken line showing of a closure is for illustrative purposes only and forms no part of the claimed design.
